(57) **CLAIM**

The ornamental design for an cartridge receptacle for audio
player, as shown and described.

DESCRIPTION

FIG. 1 is a front elevational view of an cartridge receptacle for
audio player showing my new design;

FIG. 2 is a top plan view thereof;

FIG. 3 is a rear view thereof;

FIG. 4 is a bottom plan view thereof;

FIG. 5 is a left side elevational view thereof;

FIG. 6 is a right side elevational view thereof;

FIG. 7 is a right front perspective view thereof;

FIG. 8 is a left front perspective view thereof taken from the
underside; and,

FIG. 9 is a right front perspective view thereof taken from the
underside.

The portions in broken lines represent environmental structure
only and form no part of the claimed design.
